APRON

Karl G. F. Krigsman and Mildred Krigsman,
Thompson, Conn.

Application March 22, 1949, Serial No. 1,536

Term of patent 3½ years

(Cl. D3—26)

To all whom it may concern:

Be it known that we, Karl G. F. Krigsman and Mildred Krigsman, both citizens of the United States, residing in the town of Thompson, county of Windham, State of Connecticut, have invented a new, original, and ornamental Design for an Apron, of which the following is a specification, reference being had to the accompanying drawings forming part thereof.

This application is a continuation-in-part of a design application for Princess Effect Apron, filed September 19, 1946, Ser. No. D. 133,428, which is a continuation-in-part of a design application for Princess Effect Apron, filed December 3, 1945, Ser. No. D. 124,260. Both parent applications have now been abandoned.

Fig. 1 is a front elevation of an apron, embodying our new design.

Fig. 2 is a rear elevation thereof.

Fig. 3 is a side elevation thereof.

We claim:

The ornamental design for an apron, substantially as shown.

KARL G. F. KRIGSMAN.
MILDRED KRIGSMAN.
